UNITED STATES PATENT OFFICE.

WILLIAM A. SCHURMANN, OF CHICAGO, ILLINOIS.

EGG CARTON OR CARRIER.

No. 918,601.

Specification of Letters Patent.

Patented April 20, 1909.

Application filed July 15, 1908. Serial No. 443,576.

To all whom it may concern:

Be it known that I, WILLIAM A. SCHURMANN, a citizen of the United States, residing at Chicago, in the county of Cook and State 5 of Illinois, have invented certain new and useful Improvements in Egg Cartons or Carriers, of which the following is a full, clear, and exact specification.

This invention relates to that class of egg carriers designed to be used for delivering a small number of eggs, a dozen or so, at a time, as contradistinguished from egg carriers in which large quantities are shipped, and the invention has for its primary object 10 to provide an improved, simple and efficient egg carrier of this general class which will be rigid and durable when in use, capable of being readily knocked down in compact form when not in use, and as readily set up for use 15 when desired.

Another object of the invention is to provide a box-like egg carrier or carton in which the box portion shall be capable of having its various members secured together to constitute the perfected box, and at the same 20 time be capable of folding into a compact form without necessarily detaching said members, whereby the device will be compact for shipment, but will be susceptible of 25 being readily set up or unfolded to receive the eggs or other contents.

A further object of the invention is to provide a "crush" box capable of having its sides held in position for use by the filling or 30 partitions which constitute the cells for the eggs or other contents.

With a view to the attainment of these ends and the accomplishment of certain other objects which will hereinafter appear, the invention consists in the features of 35 novelty which will now be described with reference to the accompanying drawings, and more particularly pointed out in the claim—

In said drawings, Figure 1 is a blank from 40 which the carton is made. Fig. 2 is a fragmentary perspective view of the blank partially folded to make the carton. Fig. 3 is a similar perspective view showing the members of the blank secured at one end, and the completed carton partially crushed. Fig. 4 is a perspective view showing the complete carton wholly crushed. Fig. 5 is a perspective view of the carton and the filler combined, ready for use.

55 In carrying out the invention, the box or outside portion of the carrier is preferably

composed of some thin material, such as paste board or stout paper, capable of being folded into the form of a box or receptacle, and afterward being crushed to a flat form 60 so that it may be again set up ready for receiving the contents without necessarily detaching the members of the blank, thus providing for the complete manufacture of the box at the box factory, where of course it 65 can be made and secured together with much greater facility than is possible for the user. After the carton or box portion is set up for use, the filler constituting the cells for the eggs or other contents is put within it, and 70 serves the two-fold purpose of holding the sides of the box in position while forming the partitions for holding the eggs apart.

The box or carton is preferably formed from a single piece of material in the form of 75 blank. In the exemplification of the invention shown in the drawings, the blank, whose outline is better illustrated in Fig. 1, comprises a bottom portion 1, bounded by the four-crease or fold lines 2, 3, 4 and 5; a front 80 wall or portion 6, bounded at the inner side by the three fold lines 5, 7 and 8; a back wall 9, bounded by the fold line 2 and the three fold lines 10, 11 and 12; a top or lid member 13, having a locking lip 14 adapted 85 to be folded downwardly at an angle to the lid along the fold line 15; end walls 16 and 17 at opposite ends of the bottom member 1, and stay flaps or members 18, 19 at each end of the back 9 and front 6 respectively. To form the 90 box of this blank, the front and back walls 6, 9 are turned upwardly at right angles to the bottom 1 along the lines 2, 5, and the end walls 16, 17 are similarly turned upwardly 95 along the fold lines 3, 4 respectively, after which the stay members 18, 19 at each end are turned toward each other against the outer sides of the end walls 16, 17, the stay members 18, 19 being folded or bent along 100 the fold lines 11, 12 and 7, 8 respectively, and after they are thus folded, they are secured in place in any desired way, such, for example, as by means of a staple 20 passing through the reinforced ends formed by the three members 16, 18 and 19 at one end and 105 17, 18 and 19 at the other end of the box. This constitutes the body of the box and it only remains to fold or crease the lid 13 along the line 10, when the lip 14 may be turned downwardly into the box between the inner 110 face of the wall 6 and the ends of the members 16, 17. The box or carton thus con-

2

structed may be crushed into the flat form shown in Fig. 4, without destroying the continuity of the walls or detaching the end members which hold the blank together, in 5 the form of a box. There are, of course, various methods of thus collapsing the box, which will now suggest themselves to those familiar with the invention, but one which is most effective and results not only in a neat 10 and compact package but which prevents the front wall from bulging outwardly when the box is unfolded for use consists in forcing the front wall 6 inwardly so that it will lie directly in contact with the bottom 1, then 15 folding the front corners inwardly on top of the front wall, and finally folding the rear corners downwardly and forwardly on top of the ends and over the bottom of the box, that is, so that they will lie directly in contact 20 with the outer faces of the members 18, these members in fact being folded directly upon themselves, while the top or lid lies flat across the front corners and the front wall in the same plane as the folded back, assuming 25 that the box is to be thus crushed with the lid uppermost. In Fig. 4, however, it is shown with the lid underneath for the sake of better illustration. In order that the box may be thus crushed neatly and with readiness, 30 the completely constructed box is provided with certain creases that are conducive to the structure being thus crushed always in the same form and along the same crease lines. The front wall is formed with 35 upwardly and inwardly extending creases 21 which permit the wall to be forced inwardly, and the ends of the box are formed with upwardly and inwardly extending creases 22. When the front corners are folded downwardly 40 against the face of the front wall, the upper edges thereof cross the front wall at right angles or substantially right angles to the upper edge of said wall, and these crease lines 21 extend from the point where the upper 45 edges of the end and front walls cross to the lower corners of the box. The end creases 22 are formed in both thicknesses, that is, the end wall members 16, 17 and the stay members 18. They would also occur 50 across the corners of stay members 19 if these corners were carried out in a square form, but in practice it is preferable to clip these corners off, as indicated at 19^a, and for the same reason the upper corners of the stay 55 members 18 are clipped off as shown at 18^a, thus avoiding the necessity of folding these corners when the box is crushed, which would result in leaving them protruding from the end of the box when it is again set up for use. 60 This would not only make the ends of the box unsightly, but would somewhat interfere with the box being neatly crushed. After the box has been once crushed in the manner described, it possesses a tendency to again 65 assume its crushed form after it has been

straightened out thereby preventing the front 6 from bulging outwardly away from the filler which would weaken the box, but by placing the lock-lip 14 between the inner face of the front wall 6 and the ends of the 70 end walls 17, it may be held in shape for use, even without any other internal support, but when the carton thus constructed is employed as an egg carrier, the cellular filling which holds the eggs separated is made to 75 perform the further function of preventing the walls of the box from collapsing.

In Fig. 5 of the drawings I have shown the filling in place ready to receive the eggs or other contents. This filling may be of the 80 usual or any suitable form. Of course it is desirable to employ a form capable of being collapsed, so as to lie flat like the carton itself, when not in use, but when in place in the box will combine with the box in the 85 joint duty of holding the box and the filling against collapse, it being seen that so long as the marginal members of the filling are retained in their rectangular relation to one another, the filling will be held against collapse, and as long as the end and front walls of the box are supported by the direct thrust of the longitudinal and cross members of the filling, the box cannot collapse. The filling which is preferably employed for this purpose 90 is composed of straight strips or members oppositely slotted and mortised together in the usual way, but the side and end members are preferably composed of a single instead of separate strips. This single strip 100 has its two ends brought together, as shown at 23, and after being overlapped, they are locked together by being mortised with the middle longitudinal member 24, thus making the one strip serve for forming both as ends 105 well as the sides of the filling. The other end of the middle member 24 is interlocked with the opposite end portions 25 of the said continuous strip, in the same manner, or in any other suitable way, and the three longitudinal members thus constituted are secured together and spaced by the cross members 26 which are interlocked or mortised there-with as usual. The cross members 26 and the longitudinal member 24 project slightly 110 beyond the walls of the cells, as shown at 27, 28 respectively, and hold the cell walls away from the box walls.

With an egg carrier thus constructed it will be seen that after the box or outside 120 portion is completely manufactured ready for use, it may be crushed into a comparatively flat thin form and packed together with the cellular filling for shipment in a comparatively small space and when ready 125 for use may be instantly unfolded for receiving the cellular filling and the contents without the necessity of locking the members of the blank (should the box be composed of a blank) before it can be got ready for use. 130

In order that the invention may be understood by those skilled in the art, the details of an exemplification thereof have been thus specifically described, but

5 What I claim is:

The herein - described flexible box comprising a bottom having end flaps provided with diagonal fold creases extending from the rear corners at the points of junction with 10 the bottom and outwardly toward the top edges of the flaps to points remote from the front edges thereof, a front provided with diagonal fold creases extending from the lower corners inwardly toward the top edge 15 thereof, said front having flaps beyond the diagonal fold creases separate from the flaps on the bottom, a back-wall having end flaps separate from the flaps on the bottom and provided with diagonal fold creases extending 20 from the lower corners toward the outer corners, the outer corners of the flaps on the front and rear walls being cut away, the end flaps on the front and rear walls being folded over the end flaps on the bottom and over 25 each other, a single fastening device passing

through all of the flaps for permanently securing the latter together to form reinforced end walls, and a top having a flap on its front edge adapted to be inserted within the box contiguous to the front wall for holding 30 all of the walls from collapsing, the box being adapted to be crushed or folded flat without destroying the continuity of the walls by bending the front wall inwardly on the diagonal fold creases between the end walls and 35 upon the bottom, then folding the end walls inwardly toward each other on the diagonal fold creases and over the front wall, and then the rear wall inwardly toward the front wall and over the end walls without detaching 40 the end flaps.

In testimony whereof I have signed my name to this specification, in the presence of two subscribing witnesses, on this 13th day of July A. D. 1908.

WILLIAM A. SCHURMANN.
